UNITED STATES PATENT OFFICE

NORMAN L. SNOW, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Application filed June 29, 1925. Serial No. 40,423.

The invention relates to boiler cleaners and has among its objects the provision of a rotatable discharge nozzle element capable of movement longitudinally of its axis of rotation for directing a jet of cleaning fluid adjacent the parts of the boiler to be cleaned.

Referring to the accompanying drawings in which like reference characters indicate corresponding parts;

10 Figure 1 is an elevation view partly in section showing one form of my boiler cleaner;

Figure 1^a is a detail view along 1^a—1^a of Figure 1 showing the brake retarding means for the nozzle chamber rod;

15 Figure 2 is a like view showing a modified construction of boiler cleaner;

Figure 3 is a sectional view along 3—3 of Figure 2;

20 Figures 4 and 5 illustrate further modifications of boiler cleaner constructions; and

Figure 6 is an end elevation view of the boiler cleaner shown in Figure 5.

Referring to the drawings, reference character 10 designates a blower head which may be mounted in an opening 11 of the boiler wall 12. Attached to and forming an extension of the head, is a fixed element 13 which is positioned to extend in proximity with the usual boiler tubes 14 or other parts of the boiler to be cleaned. The element 13 is provided with a plurality of ports or openings 15 which are spaced longitudinally of the element at predetermined points. 16 represents a travelling nozzle chamber adapted for movement longitudinally within the fixed element 13 and carrying one or more discharge nozzles 17. 18 represents a plate or head closing the rear end of the nozzle chamber. Secured within the forward end 40 of the nozzle chamber is a spider 19 having openings 20 for affording passage of cleaning fluid from the blower head 10 to the nozzle 17. 21 is a nozzle chamber rod fixed to the spider 19 and provided with a circular rack portion 22 extending forwardly through the blower head. Cleaning fluid is admitted through a supply line 23 to the blower head 10 and thence to the nozzle 17, the supply of cleaning fluid being controlled by a valve 24.

Ball bearing 25 is provided and is held by a bracket 26 secured to the soot blower head for taking the outward reaction of the thrust produced by the cleaning fluid. 27 is a crank fitted with a gear 28 meshing with the circular rack 22 whereby the nozzle chamber 16 may be given a longitudinal movement to return the nozzle chamber after it has been projected under the influence of the cleaning fluid as hereinafter described. 55 A second gear 29 is positioned to mesh with the circular rack 22 and is fitted with a hammer 30, which at each rotation of the gear 29 will strike a bell 31 to indicate that nozzle 17 is properly registered with one of the openings 15. 32 is a crank provided with a key 12^a engaging a keyway 12^b in the circular rack 22 for imparting a rotary movement to the nozzle chamber, and hence the nozzle 17, for moving the latter through any desired 60 arc. The key 12^a may slide in the keyway 12^b when crank 27 is actuated. For accommodating the desired length of arc of travel of the jet of cleaning fluid discharged from the nozzle 17 the openings 15 may be of appropriate arcuate length. 65

Referring to Figure 1^a I have shown a brake retarding device for applying a retarding force to the nozzle chamber rod when the latter is acted upon by the piston effect 80 of the cleaning fluid tending to project the nozzle chamber into the portion of element 13 within the boiler. The cleaning fluid acting on the head 18 tends to project the nozzle chamber and rod 21 longitudinally inwardly 85 of the boiler wall. While considerable friction may be established between the nozzle chamber 16 and the element 13 to check the movement of the nozzle chamber under the influence of the cleaning fluid, it may be desirable to further restrain undue movement of the nozzle chamber by means of the device shown in Figure 1^a. The crank 27, for this purpose, has an extension 27^a to which is fixed a brake drum 27^b engageable by a brake band 27^c. The ends of this band may be contracted to cause the band to frictionally engage the brake drum by any suitable means such as a knurled member 27^d as will be readily understood. By retarding the brake drum, a re- 90 95 100

tarding of the nozzle chamber rod is produced through engagement of the gear 28 and rack 22. Thus the knurled member 27^d may be operated to control the movement of the nozzle chamber rod under the influence of the cleaning fluid.

Where the friction between the nozzle chamber and element 13 is sufficient to retard the movement of the nozzle chamber under the influence of the cleaning fluid, the 10 crank 27 may be employed to impart movement to the nozzle chamber both in aligning the nozzle 17 with the openings 15 as well as in returning the nozzle chamber to its original 15 position.

In operation of the boiler cleaner construction as shown in Figure 1, cleaning fluid is admitted to the blower head 10 by means of the valve 24, the cleaning fluid passing to the 20 nozzle chamber 16 and the discharge nozzle 17 tending to project the nozzle chamber. The operator then releases the brake band 27^c until the bell 31 sounds to indicate that the nozzle 17 is in register with the first or 25 other desired opening 15. The operator then contracts the brake band 27^c by the knurled member 27^d to hold the nozzle chamber against further movement and then rotates the crank 32 causing the jet of cleaning fluid 30 from the nozzle 17 to travel through the desired arc for cleaning the parts of the boiler located in the part of the jet. The skirt or body of the nozzle chamber will be made sufficiently long to close all of the openings 15 in the rear of that opening with which nozzle 17 is in registration. The operator then again releases the brake band 27^c to permit 35 movement of the nozzle chamber to register the nozzle 17 with the next opening of the element 13 and the cleaning process is thus 40 repeated throughout the length of the fixed element 13 or any desired portion thereof. The crank 27 is employed to return the nozzle chamber after the cleaning fluid has been 45 shut off.

Referring to Figure 2 the blower head 10^a is shown provided as before, with a fixed element 13^a having the arcuate openings 15^a. 16^a represents the nozzle chamber shown in this instance as provided with a pair of diametrically opposed discharge nozzles 17^a. It is understood that any desired number of nozzles may be provided. 19^a represents the spider having the openings 20^a for accommodating the passage of cleaning fluid as best shown in Figure 3. The nozzle chamber rod 21^a in this instance is fitted with turbine rotors 33. These rotors may be provided with keys fitted into the keyway 12^c so that 50 rotors 33 will drive the rod 21^a while permitting the rod 21^a to slide relative to the rotors. Stationary blades 34 are provided for directing the fluid toward the turbine rotors 33 55 for imparting rotary movement to the latter in accordance with the usual turbine practice.

The blades 34 may be held in place by their frictional engagement with the inner walls of element 13^a, the rod 21^a freely rotating and sliding relative to these blades. In order to prevent any tendency of the outer rotor 33 to move to the left, as seen in Figure 2, when the rod 21^a is actuated by the crank 27, the set screw members 12^d may be provided. These members 12^d may be screwed in the walls of element 13^a and may be provided with rounded ends 13^e engaging the face of the rotor so as to minimize friction at this point. In this construction, the fluid for actuating the turbine is the cleaning fluid which passes from the head 10^a to the discharge nozzles 17^a. Thus, the turbine functions as a pressure reducing medium for reducing the pressure of the cleaning fluid in passing from the supply line 23 to the nozzles 17^a. With such construction the use of an orifice plate 85 or reducing valve for effecting such reduction in pressure of the cleaning fluid is avoided. It will further be noted that the exhaust from the turbine passes to the discharge nozzles 17^a. The nozzle chamber 16^a may be 90 progressively longitudinally moved and controlled as before described to align the nozzles 17^a with the openings 15^a by the crank 27 or a brake control device operating in the manner similar to the boiler cleaner shown 95 in Figure 1. In the construction shown in Figure 2 it will be apparent that power means is provided for imparting a rotary movement to the discharge nozzles and that the cleaning fluid will exert a force tending 100 to project the nozzle chamber, which force may be supplemented by manual actuation of handle 27.

With reference to the construction shown in Figure 4, 10^b represents the blower head 105 provided with the fixed element 13^b. Telescoped for longitudinal movement within the fixed element 13^b is a movable element 37 formed at its forward end with an annular shoulder 35 adapted for engagement with a 110 corresponding shoulder 36 of the element 13^b for limiting the outward movement of the movable element 37. The element 37 is provided with arcuate openings 38 permitting discharge of the jets of cleaning fluid from the nozzles 17^b carried by the nozzle chamber 16^b. In this construction the nozzle chamber is not movable longitudinally relatively to the element 37 but is adapted for relative 115 rotative movement with respect to the element 37. 19^b indicates a spider having openings 20^b functioning as before. 39 is a turbine of the spiral bladed or screw type mounted on a shaft 40 fixed with the spider 19^b. 21^b is the nozzle chamber rod secured to the 120 spider 41 which in turn is secured to element 37 for imparting longitudinal movement to the element 37. The forward end of the rod 21^b has a portion 22^b threadedly engaging the head 10^b as at 22^c to produce longi- 125 130

tudinal feeding of the rod, and has a splined engagement with the wheel 28^b. Thus wheel 28^b may be provided with a key engaging in the keyway 12ⁱ, the wheel 28^b having its bearing in the brackets 12^e and permitting the threads of the rod 21^b to pass freely through the hub portion of the wheel.

A leak-off 42 with drain valve 43 may be provided to take care of the leakage from the head.

In operation of the construction shown in Figure 4, the cleaning fluid passes from the supply line 23 and acts upon the turbine 39 to impart a rotary movement to the nozzle chamber 16^b and the discharge nozzles 17^b as in the construction shown in Figure 2. By rotating the wheel 28^b the rod 21^b is rotated and by reason of the threaded engagement of the rod in head 10^b this rod is moved longitudinally to position the element 37 carrying with it the nozzle chamber 16^b in any desired position with respect to the parts of the boiler to be cleaned. If desired, the threaded engagement of the rod in the head may be eliminated and the rod portion 22^b may be provided with a brake restraining device as shown in Figure 1^a.

With reference to the constructions shown in Figures 5 and 6, automatic means is provided whereby the travelling nozzle is projected in a step by step movement under the influence of the pressure of the cleaning fluid. Means is also provided whereby the period of travel of the nozzle may be fixed so as to release the nozzle after it has been rotated in any given position for a given number of revolutions, the cleaning fluid pressure then advancing the nozzle to the next point where it is again held in fixed position until it has made a predetermined number of revolutions at this point. In these figures 10^c indicates the blower head which may cooperate with either of the constructions shown in Figures 2 or 4. 22^c represents the circular rack forming the forward extension of the nozzle chamber rod 21^c. 44 is a gear meshing with the circular rack 22^c and fixedly mounted on a shaft 45 which is journaled in the bifurcated ends 46 of a bracket 47 carried by the blower head 10^c. 48 represents a stop fixed to one of the arms 46 and positioned to extend in the path of a trigger 49 which is rotatable with the shaft 45. The trigger 49 is pivotally mounted at 50 on the shaft 45 whereby it may be rocked out of engagement with the stop 48. 51 represents a spring for normally maintaining the trigger in a position perpendicular with the axis of shaft 45 for engagement with the stop 48. 52 is a second bracket fixed with the blower head 10^c for providing a bearing for a shaft 53 upon which a wheel 54 is rotatably mounted. The wheel 54 is provided with a plurality of suitably arranged radially projecting arms 55 adapted for engagement with the trigger 49.

for disengaging the latter from the stop 48. The wheel 54 is also provided with the pins 55 adapted to be engaged by a pin 56 carried by the wheel 57 for imparting a step by step rotative movement to the wheel 54 as the wheel 57 is rotated. The latter wheel has a key 12^h engageable in the keyway 12ⁱ to rotate with the circular rack 22^c. When the rod 22^c is moved longitudinally the key 12^h is free to slide in the keyway 12ⁱ.

In operation of the boiler cleaner shown in Figures 5 and 6 the outward thrust of the cleaning fluid on the end of the nozzle chamber will tend to move the circular rack 22^c inwardly and thus rotate gear 44 and shaft 45 until the trigger 49 engages the stop 48. In this position the circular rack 22^c is held from further inward movement while the turbine is being rotated under the influence of the cleaning fluid to direct the jet of cleaning fluid in the arcuate path for cleaning the parts of the boiler. If this construction is used in connection with the device shown in Figure 2, this position of the parts will correspond to an alignment of the nozzles 17^a with an opening 15^a. As the turbine is actuated to rotate the discharge nozzle the wheel 57 is also rotated causing the pin 56 to act on the pins 55 of wheel 54 to impart a step by step rotative movement of the latter. Continued rotation of the wheel 57 for any predetermined number of rotations will cause one of the radial arms of wheel 54 to engage the trigger 49 and move the latter against the action of spring 51 out of the path of the stop 48. The shaft 45 will then be free to rotate and the nozzle chamber and the circular rack 22^c will be moved longitudinally under the piston effect exerted by the cleaning fluid until the trigger 49 is again engaged by the stop 48. The spring 51 serves to restore the trigger 49 to its normal position as soon as the shaft 45 has been rotated sufficiently to disengage the trigger 49 and stop 48. The circular rack or rod 22^c may be returned to its initial position by a crank and pinion such as shown in Figures 1 and 2. The cycle is thus continued. By suitably arranging the various parts of the mechanism, the longitudinal distance travelled by the nozzle between each of the successive points of operation may be varied as desired. Also, the time of rotation of the nozzle at each of these points may be conveniently regulated.

By the term "rotation" as used throughout the specification and claims, I mean one or more complete or partial rotative movements of the discharge nozzle.

What I claim as my invention is:

1. In a boiler cleaner, a head, an element fixed relatively with the head and extending into proximity with parts of the boiler to be cleaned said element provided with an opening, a member rotatable in said element, said member being provided with a discharge

nozzle and being slidable longitudinally of said element to register said nozzle with the opening of the element, means for supplying steam to the head and member for discharge through said nozzle to clean parts of the boiler, and means for utilizing the force of the steam to move said member longitudinally of the element and to rotate said member.

2. In a boiler cleaner, a head, an element fixed with respect to the head and provided with a plurality of longitudinally spaced openings a member provided with a discharge nozzle movable longitudinally of the element to successively register the nozzle with the openings, means for supplying a cleaning fluid to said nozzle by way of said element for discharge through said nozzle toward parts of the boiler to be cleaned, and means operable to temporarily check the longitudinal movement of the said member each time its discharge nozzle registers with one of the openings in said element.

3. In a boiler cleaner, a head, an element fixed with respect to the head and provided with a plurality of longitudinally spaced openings, a nozzle chamber provided with a discharge nozzle slidable longitudinally within said element to successively register said nozzle with the openings of the element, means for supplying a cleaning fluid to the head and thence to the nozzle chamber by way of said element whereby the cleaning fluid may be discharged through said nozzle when the latter is aligned with the respective openings, means for moving said nozzle chamber longitudinally of the element and additional means operable to periodically check the longitudinal movement of said nozzle chamber.

4. In a boiler cleaner, a head, an element fixed with respect to the head and provided with a plurality of longitudinally spaced openings, a nozzle chamber provided with a discharge nozzle slidable longitudinally within said element to successively register said nozzle with the opening of the element, means for supplying cleaning fluid to said nozzle chamber for discharge through said nozzle and through the openings of said element toward parts of the boiler to be cleaned, fluid pressure actuated means for moving said nozzle chamber longitudinally of the element, and means for rotating said nozzle when the nozzle is brought into register with said openings.

5. In a boiler cleaner, a head, an element fixed with respect to said head and provided with a plurality of openings spaced longitudinally of the element, a member provided with a discharge nozzle movable longitudinally of the element to successively align the nozzle with the openings, means for supplying a cleaning fluid to said head and thence to the nozzle, means for indicating the position of the nozzle with respect to the openings of

the element, and means for moving the member longitudinally of the element.

6. A boiler cleaner comprising an element provided with an opening, a nozzle chamber located within the element and provided with a discharge nozzle adapted to register with said opening, means for moving the nozzle chamber longitudinally, a fluid actuated turbine connected to operate said nozzle chamber, and means for supplying a cleaning fluid to act on said turbine for causing a rotative movement of the nozzle chamber.

7. A boiler cleaner comprising a discharge nozzle adapted to be rotated, a fluid actuated turbine connected to rotate said nozzle, means for supplying fluid to the turbine and nozzle, means for imparting a longitudinal movement to said nozzle and means for periodically checking the longitudinal movement of the nozzle to cause the same to advance in steps.

8. A boiler cleaner comprising a discharge nozzle adapted to be rotated, a fluid actuated turbine connected to rotate said nozzle, means for supplying fluid to the turbine and nozzle, and means for imparting a step by step longitudinal movement to the turbine and nozzle as a unit.

9. A boiler cleaner comprising a rotatable discharge nozzle adapted to be moved longitudinally of the axis of rotation for locating said nozzle at a plurality of predetermined points with respect to the boiler to be cleaned, means for supplying a cleaning fluid to said nozzle, and means actuated by the pressure of the cleaning fluid for automatically periodically moving said nozzle longitudinally of its axis of rotation to locate the nozzle at said plurality of predetermined points and for imparting a rotary movement to the nozzle when it is positioned in said predetermined points.

10. A boiler cleaner comprising a head, an element fixed relative to said head and provided with a plurality of openings spaced longitudinally thereof at predetermined points, a discharge nozzle chamber movable longitudinally within said element and provided with a nozzle adapted to successively register with said openings, a fluid actuated turbine for imparting rotary movement to said chamber and nozzle, means for supplying a cleaning fluid to said turbine and nozzle, and means for automatically advancing said nozzle to register with the successive openings, said last named means automatically acting after the nozzle has been in alignment with any of said openings for a predetermined time.

11. In combination with a rotatable boiler cleaner discharge nozzle adapted to be moved in a step by step movement longitudinally of the axis of rotation to locate the nozzle at a plurality of predetermined positions, means for supplying a cleaning fluid to said nozzle, and means operable upon the supplying of

cleaning fluid to said nozzle to automatically impart a step by step movement to said nozzle whereby the nozzle is moved from any one of said positions to the next, said last named means automatically acting after the 5 nozzle has been in any one of said positions for a predetermined length of time.

12. A boiler cleaner comprising a rotatable discharge nozzle adapted to be moved longitudinally of the axis of rotation for locating 10 said nozzle at a plurality of predetermined points with respect to the boiler to be cleaned, means for supplying a cleaning fluid to said nozzle, the pressure of said cleaning fluid being utilized to impart both rotative and longitudinal movement to said nozzle, and means restricting the flow of the cleaning fluid from the nozzle to such positions of the nozzle as correspond with said predetermined points. 15

13. A boiler cleaner comprising a head, 20 an element provided with an opening, a nozzle chamber located within the element and provided with a discharge nozzle adapted to register with said opening, means including 25 a shaft threaded in said head for effecting a longitudinal movement of said nozzle chamber, a fluid actuated turbine connected to operate said nozzle chamber, and means for supplying a cleaning fluid to act on said turbine 30 for causing a rotative movement of the nozzle chamber.

In testimony whereof I affix my signature.
